(57) **CLAIM**

The ornamental design for an intravenous bag/line safety label, as shown and described.

DESCRIPTION

FIG. 1 is a top plan view of one embodiment of an intravenous bag/line safety label of our new design, that portion shown in broken lines is not part of the claimed design and is provided for environmental purposes only.

FIG. 2 is a bottom plan view of the embodiment of the intravenous bag/line safety label of FIG. 1, that portion shown in broken lines is not part of the claimed design and is provided for environmental purposes only.

FIG. 3 is a side elevational view of the embodiment of the intravenous bag/line safety label of FIG. 1, that portion shown in broken lines is not part of the claimed design and is provided for environmental purposes only.

FIG. 4 is a front elevational view of the embodiment of the intravenous bag/line safety label of FIG. 1, that portion shown in broken lines is not part of the claimed design and is provided for environmental purposes only.

FIG. 5 is a rear elevational view of the embodiment of the intravenous bag/line safety label of FIG. 1, that portion shown in broken lines is not part of the claimed design and is provided for environmental purposes only.

FIG. 6 is a top plan view of another embodiment of an intravenous bag/line safety label of our new design, that portion shown in broken lines is not part of the claimed design and is provided for environmental purposes only.

FIG. 7 is a bottom plan view of the embodiment of the intravenous bag/line safety label of FIG. 6, that portion shown in broken lines is not part of the claimed design and is provided for environmental purposes only.

FIG. 8 is a side elevational view of the embodiment of the intravenous bag/line safety label of FIG. 6, that portion shown in broken lines is not part of the claimed design and is provided for environmental purposes only.

FIG. 9 is a front elevational view of the embodiment of the intravenous bag/line safety label of FIG. 6, that portion shown in broken lines is not part of the claimed design and is provided for environmental purposes only; and,

FIG. 10 is a rear elevational view of the embodiment of the intravenous bag/line safety label of FIG. 6, that portion shown in broken lines is not part of the claimed design and is provided for environmental purposes only.

1 Claim, 6 Drawing Sheets
